UNITED STATES PATENT OFFICE.

SIDNEY C. SLADDEN, OF NEW YORK, N. Y.

SERVICE-BRACKET FOR TELEPHONE-RECEIVERS.

1,384,101.

Specification of Letters Patent. Patented July 12, 1921.

Application filed July 31, 1919. Serial No. 314,455.

To all whom it may concern:

Be it known that I, SIDNEY C. SLADDEN, a citizen of the United States, and a resident of New York city, in the county and State 5 of New York, have invented certain new and useful Improvements in Service-Brackets for Telephone-receivers, of which the following is a full, clear, and exact description.

Among the principal objects which the 10 present invention has in view are: to avoid the necessity for manually supporting a telephone receiver while the same is in active service; to enable the person using a telephone to employ both hands during said active service; to increase the efficiency of the 15 telephone service; to compel the user of the telephone to talk directly into the mouthpiece; to open and close the circuit more quickly than the present construction; to accommodate the bracket for use in conjunction 20 with telephone instruments of usual construction; and to simplify and reduce the cost of the character brackets herein described.

25 Drawings:

Figure 1 is a side view of a telephone instrument having attached thereto, a bracket constructed and arranged in accordance with the present invention, the receiver being in 30 the active service position.

Fig. 2 is a front view of the same, the receiver being shown in the inactive position of the telephone instrument.

Fig. 3 is a detail view showing a top view 35 of the telephone supporting bracket in its folded or inactive position.

Fig. 4 is a top plan view of a telephone instrument showing a modified form of the invention and attachment thereto.

40 Fig. 5 is a detailed view on enlarged scale showing fragments of the supporting arm and stiff arm and the means for uniting the same adjustably and pivotally, portions of the two arms being shown in section for dis- 45 closing the interior construction.

Fig. 6 is a detailed view showing a side view of said fragments of the supporting arm and stiff arm, the adjusted positions of the latter being indicated by broken lines.

50 Description:

As seen in the drawings, the pedestal 11, the transmitter 12 and the receiver 13 and hook 14 are constructed and arranged as is usual with telephone instruments.

55 When employing the present invention,

the bracket is secured to the pedestal by means of a rigid collar 15. The collar 15 has a swinging jaw 16 perforated to receive a wing nut 17, the threaded end of which engages the extremity of the collar 15, as seen 60 best in Fig. 3 of the drawings.

Rigidly mounted on the collar 15 is an arm 18, at the opposite end whereof is provided an angularly disposed screw-threaded extension 19. Thread-engaging the extension 19 is a stiff arm 20. At the free extremity of the stiff arm 20 is a split ring 21 which in service forms a supporting collar for the telephone receiver 13. To this end the ring 21 has a number of over-turned lugs 70 22, which extend over the side of the roll generally provided on the cap of the receiver, which normally houses the diaphragm of the said receiver.

The inactive position of the telephone receiver, when employing a bracket constructed and arranged in accordance with the present invention, is shown in Fig. 2 of the drawings. In this position the weight of the receiver 13 rests on the hook 14 to depress the 75 same for breaking the telephone circuit. When it is desired to use the telephone, the receiver is lifted, swinging the arm 20 and the receiver held thereby, to the position shown in Fig. 1. The arm 20 pivots in the 80 collar 19. The screw thread at the ends of the arm 20 carries the same into the collar 19.

It is obvious that the extent to which the ends of the arm 20 can enter the collar 19 governs the angular disposition of the arms 90 20 and 18. It is for this purpose that the end of the arm 20 is bored and tapped to receive the screw 23, as is shown best in Fig. 5 of the drawings.

As the screw 23 is advanced or retracted, 95 the arm 20 relative to the arm 18 is checked or released. This permits the adjustment of the active service position of the receiver 13 to the ears of different persons.

It is obvious that when it is desired to 100 discontinue the use of the telephone, the receiver is rotated about the pivot formed by the collar 19 and the end of the arm 20 to rest on the hook 14 in the position shown in Fig. 2.

In Fig. 4 of the drawings the modification of the invention is disclosed. The modification consists in employing a second stiff arm 24. The stiff arm 24 is made up 110 in two parts, the parts being connected by

a spring 25. The remainder of the structure is, to all intents and purposes, the same as that above described.

The ring 21 is employed in this case to hold the "watch" receiver 26, and the purpose of the resilient connection or spring 25 is to maintain automatically the "watch" receiver 26 in contact with the ear of the person using the telephone. The contact 10 between the receiver 13 and the ear of the person is manually accomplished by the person leaning against the receiver 13. In all positions of the head of the person using the telephone, the spring 25 pushes the receiver 26 against the opposite ear of the user. 15

It is obvious that while I have described the connection between the telephone holder and the pedestal of the telephone, using the collars 15 and nut 17, other means for holding the stiff arm 18 may be employed. In fact the stiff arm 18 may be, if desired, connected with the base of the telephone to extend upward therefrom. This has not been illustrated, as it is considered an obvious 25 alternative of the construction disclosed.

Claims:

1. A support as characterized comprising, an arm for engaging a telephone receiver; means for pivotally mounting said arm so 30 that the end thereof holding said receiver may be moved to dispose said receiver upon the receiver hook of a telephone associated therewith to establish the inactive condition of said telephone; and means for adjusting 35 at will the active position of said arm.

2. A support as characterized comprising, an arm for engaging a telephone receiver; means for pivotally mounting said arm so 40 that the end thereof holding said receiver may be moved to dispose said receiver upon the receiver hook of a telephone associated therewith to establish the inactive condition of said telephone; and means for adjusting the active position of said arm, said means embodying a stop screw adapted for engaging 45 said arm when the same is moved to the active position thereof.

3. A support as characterized comprising, an arm for engaging a telephone receiver; means for pivotally mounting said arm so 50 that the end thereof holding said receiver may be moved to dispose said receiver upon the receiver hook of a telephone associated therewith to establish the inactive condition of said telephone; and a second arm for 55 holding in active position an auxiliary receiver.

4. A support as characterized comprising, an arm for engaging a telephone receiver; means for pivotally mounting said arm so 60 that the end thereof holding said receiver may be moved to dispose said receiver upon the receiver hook of a telephone associated therewith to establish the inactive condition of said telephone; a second arm for holding 65 in active position an auxiliary receiver; and means for yieldingly maintaining the active position of said auxiliary receiver.

SIDNEY C. SLADDEN.
